(57) **CLAIM**

The ornamental design of a bottle opener, substantially as shown and described.

DESCRIPTION

FIG. 1 is a bottom perspective view of a bottle opener of a first embodiment of the present disclosure showing my new design.

FIG. 2 is a left side view thereof.

FIG. 3 is a right side view thereof.

FIG. 4 is a front view thereof.

FIG. 5 is rear view thereof.

FIG. 6 is a bottom view thereof.

FIG. 7 is a top view thereof.

FIG. 8 is a bottom perspective view of a bottle opener of a second embodiment thereof.

FIG. 9 is a left side view thereof.

FIG. 10 is a right side view thereof.

FIG. 11 is a front view thereof.

FIG. 12 is rear view thereof.

FIG. 13 is a bottom view thereof; and,

FIG. 14 is a top view thereof.

The features shown in broken lines in the drawings are for illustrating environmental structure and form no part of the claimed design.

1 Claim, 14 Drawing Sheets
